ABSTRACT

Microwave heating apparatus comprising a conveyor band carrying material through a split folded waveguide comprising straight and curved elements, the slots in the straight elements for the passage of the conveyor having lips which are not more than one-eighth of the wavelength apart.

2 Claims, 4 Drawing Figures

Patented July 17, 1973

SPLIT FOLDED WAVEGUIDE WITH LEAKAGE PREVENTIVE APERTURES

Preferably, the straight elements are in even number, the length of the curved elements does not equal a whole multiple of a half-wavelength, the lips are grooved and the conveyor band carries the material from the end of the waveguide most remote from the microwave generator in the direction of the latter. Other features of the invention are disclosed in the specification and drawing.

Microwave heating has, in principle, the advantage of speed. The conditions of its application, however, vary enormously with the materials.

The present invention concerns an apparatus for microwave heating granulated material, in particular for roasting cocoa beans and freeze-drying.

The principle of roasting cocoa beans on a conveyor belt by means of a high frequency electric field was published not later than 1960. The process and apparatus described, however, are suitable only for frequencies in the range of 10 to 60 Megahertz.

Using appreciably higher frequencies, however, is an advantage. The electric field strength is limited, particularly with moisture-containing materials, by the danger of arcing, and for a given electric field intensity, the energy transmitted to the material is proportional to the frequency.

Similarly, the heating time decreases with the increase of the frequency.

On the contrary, the penetration decreases with the frequency and therefore, the heating is less uniform; this imposes an upper limit to the frequency.

Taking into account the frequency ranges legally prescribed for this kind of operation, there is an advantage in using a frequency range between 2,400 and 2,500 Megahertz.

In this range of frequencies, an apparatus with two electrodes (resonant cavity) cannot be used and in practice, waveguides are necessary. It is also known that the dimensions and shape of the wave guides are determined by the frequency.

For industrial applications, the waveguide itself cannot be used as a tunnel. As mentioned before the dimensions of the waveguide are closely related to the frequency and for the frequencies considered, the width of the waveguide would be some 5 cm only. It is evident that this would not provide a passage large enough for a throughput of material on an industrial scale.

Moreover, the distribution of the electric field along the waveguide would be extremely difficult to determine because of the major influence of the moisture of the material (up to 15 percent) and its variation along the tunnel. The length of the tunnel could be found only by lengthy trial and error.

Finally, the opening necessary for the passage of the material would cause losses and disturb the operation.

The invention provides a solution to these difficulties. It concerns an apparatus of the kind described, comprising a conveyor band carrying the material to be treated, a microwave generator and a split folded waveguide, the said waveguide having straight elements perpendicular to the direction of travel of the conveyor band, connected by curved elements, said straight elements being provided with slots for the passage of the conveyor band and the material, and said slots having

lips, the distance between said lips being not more than one-eighth of the wavelength in the waveguide.

The annexed drawing represents, by way of example, an embodiment of the invention.

FIG. 1 is a plan view.

FIG. 2 is a section of a transversal element of the waveguide along the line II - II of FIG. 1.

FIG. 3 is an enlargement of a detail of FIG. 2.

FIG. 4 is a diagram of the stationary waves in two elements of the waveguide.

In the drawing, the apparatus comprises a microwave generator 1 connected to a split folded waveguide 2. This waveguide has several straight elements 21, 22, 23, 24 . . . connected by curved elements 31, 32, 33 . . . and ends in an absorber 4 made of a water load or a cavity with ferrite walls. This absorber is here purely as a safety measure because the energy emitted by the generator must be completely absorbed at the end of the waveguide for maximum efficiency. In this respect, the split folded waveguide has the advantage that straight elements can be added or removed to improve the efficiency.

The apparatus also comprises a conveyor band 5 driven by a motor 6. This band is very thin and made of a material which is "transparent" to microwaves, such as polytetrafluoroethylene (teflon) to prevent disturbances in the energy distribution. In another embodiment, the conveyor band is replaced by a vibrating bed. Preferably the surface of the band is grained to reduce slippage between the band and the material carried on it. At the input end of the conveyor band, a device equalises the thickness of the layer of material.

The band passes through slots in the straight elements of the waveguide. The shape of these slots can be seen on FIGS. 2 and 3. FIG. 2 is a section through a waveguide element. The conveyor band 5 carries the material 7 and both pass through a slot 8 in the wall of the waveguide. The slot has lips 9, the distance between them being not more than one-eighth of the wavelength in the waveguide. By these means the energy cannot propagate itself through this channel and the latter forms a sort of trap preventing any leakage of energy.

In the simplified form represented in FIG. 2, the energy retained is reflected into the waveguide and tends to disturb the general distribution of energy inside the same. To prevent this inconvenience, the lips 9 are grooved inside as in 10 and the depth (1) of the groove is approximately equal to the distance h between the lips. The cavity (of approximately square section) thus formed acts as a resonator in which the energy leakages remain stationary (FIG. 3). This form is particularly necessary when the width of the slot (h) approaches a given fraction of the wavelength (λ_g) in the waveguide. This fraction varies with the products; with cocoa beans (a difficult case because of their relatively large size) it is approximately one-eighth.

It has been found in some cases that there is an advantage in extending the lips from one waveguide element to the other, forming a tunnel 13 between these elements.

As an outlet for the water vapour coming out of the material, perforations are provided in the wall of the waveguide and/or of the tunnel. It has been found that if the diameter of the perforations does not exceed one-fortieth of the wavelength, there are no energy losses. The perforations in the wall of the tunnel can even be

larger because the energy leaking out of the lips and reaching the walls of the tunnel is very small.

The energy distribution along the waveguide is diagrammatically represented in FIG. 4. The energy forms stationary waves with troughs 11 and peaks 12. In order that the energy is regularly spread on the whole width of the band 5, it is an advantage to shift the stationary waves of one element relatively to the ones of the next element, as shown in FIG. 4. To obtain this, the curved element 3 should be of appropriate length, and must not equal a whole multiple of a half-wavelength.

Finally, the energy is progressively absorbed along the waveguide and therefore, if the power at the inlet of the upper element of FIG. 4 is 5W, by way of example, and is 4W at the outlet of this element, it will also be 4W at the inlet of the lower element and 3W at the outlet of the latter.

This purely arbitrary example is meant to show that the distribution of energy on the width of the band is symmetrical if the straight elements of the waveguide are in even numbers. In FIG. 4, a power decrease from right to left in the upper element is balanced by a power decrease from left to right in the lower element. Adding the figures shows also this symmetry: on the left, $4W + 4W = 8W$, on the right, $5W + 3W = 8W$. There is an advantage, therefore, in providing an even number of straight elements.

It would seem to be advantageous to let the material travel in the same direction as the energy, that is from right to left in FIG. 1. In this way, the maximum energy would be applied to the material with the maximum moisture content, and the minimum to the dried material. In fact, experience has confirmed that it is better to do the opposite, that is to displace the material from the end of the waveguide most remote from the microwave generator in the direction of the latter.

EXAMPLE 1

The apparatus is intended for roasting cocoa beans. The generator provides 1,250W at $2,450 \pm 25$ 40 Megahertz, to which corresponds a wavelength of 12.24 cm in space. The generator is connected to a waveguide type WR430 in which the wavelength λ_g is 14.7716 cm. The straight elements of the waveguide are perforated with circular holes of 3 mm diameter. The height of the slots for the passage of the band and the material is 18 mm. The beans, with a maximum diameter of 14 mm and an initial water content of 6.5 percent, are delivered at a rate of 15 kg/h. They are carried by a grained teflon band of 0.25 mm thickness and progress at 0.7 m/minute approximately. The beans travel approximately 2 metres in 4 minutes. Their moisture content at the outlet is approximately 2 percent.

55

With a layer of cocoa beans of 15 mm thickness having a maximum water content of 15 percent, experience has given the following dimensions for the lips:

$$h = l = 18 \text{ mm}$$

$$(\lambda_g / 8 = 14.77 \text{ cm} / 8 = 18.5 \text{ mm})$$

$$l' = 25 \text{ mm}$$

$$h' = 2 \text{ mm}$$

Between the straight waveguide elements are placed tunnels made of aluminium sheet of 2 mm thickness with square perforations of 5 mm width and 6.5 mm between axes.

EXAMPLE 2

The apparatus is intended for freeze-drying frozen coffee extract. The generator provides 1,500W. The frequency, the wavelengths, the type of waveguide and the diameter of the perforations in the latter are the same as in Example 1. The height of the slots for the passage of the band and the material is 14 mm, the thickness of the product layer 10 mm, the water content (in the form of ice) of the latter is 55 percent. The material is carried by a grained teflon band of 28 cm width and 0.25 mm thickness travelling at 0.2 m/minute. The slippage being negligible, the output is 6 kg/h and the water content at the outlet 2 percent.

The slot being narrower and the loss factor of the product smaller than in Example 1, it was possible to dispense with the grooves in the lips which were formed of plain angle-irons; in this case therefore $h' = 0$ and $h = l = l' = 14 \text{ mm}$. For the same reason, the tunnel between the straight waveguide elements could be dispensed with.

I claim:

1. Microwave heating apparatus comprising a conveyor for carrying the material to be treated, a microwave generator and a split folded waveguide, the said waveguide having straight elements perpendicular to the direction of travel of the conveyor and curved elements alternately connecting said straight elements, said straight elements being provided with slots for the passage of the conveyor and the material and having spaced upper and lower lips adjacent said slots, each of said lips being provided with inwardly extending grooves together forming a resonator, the separation between said lips being not more than one-eighth of the wavelength in the waveguide.

2. Microwave heating apparatus according to claim 1, in which the width of the lip grooves is approximately one-ninth of the lip separation.
